UNITED STATES PATENT OFFICE

GEORGE ALBERT LYON, OF ALLENHURST, NEW JERSEY

DESIGN FOR AN AUTOMOTIVE TIRE COVER

Application filed November 18, 1931. Serial No. 41,766. Term of patent 14 years.

To all whom it may concern:

Be it known that I, GEORGE ALBERT LYON, a citizen of the United States, and residing in the city of Allenhurst, in the county of Monmouth and State of New Jersey, have invented a new, original, and ornamental Design for an Automotive Tire Cover or Similar Article, of which the following is the specification, reference being had to the accompanying drawing forming a part thereof.

In the drawing:

Figure 1 is a side view of my cover.

Figure 2 is a plan view of the cover.

The two figures illustrate a spare tire cover having a lustrous metallic surface enveloping the tread portion of the tire, and presenting, when viewed from the side, a relatively deep dull side wall band encircled by a relatively narrow lustrous band.

I claim:

The ornamental design for an automotive tire cover as shown and described.

GEORGE ALBERT LYON.

CERTIFICATE OF CORRECTION.

Design Patent No. 88,359.

November 22, 1932.

GEORGE ALBERT LYON.

It is hereby certified that error appears in the above numbered Design patent requiring correction as follows:

In the drawing Figure 1, should appear as shown below instead of as shown in the present drawing of the patent;

Fig. 1

and that the said Letters Patent should be read with this correction therein that the same may conform to the record of the case in the Patent Office.

Signed and sealed this 20th day of December, A. D. 1932.

(Seal)

**M. J. Moore,
Acting Commissioner of Patents.**
